**HANDLE CONTROL FOR TONGUE HITCH
DROP PIN**

Steven Schmidt, Webster, Wis.

Application April 6, 1956, Serial No. 576,585

2 Claims. (Cl. 280—515)

This invention, a hitch for connecting the tongue of a wagon or of various other implements or vehicles to the draw bar of a tractor, may be summarized briefly as follows:

Secured to a tongue for swinging movement in an up-and-down direction is an arm having at one end a depending pin engageable in an opening of the draw bar. At one end of the arm is an eccentric washer adjustable about its axis into engagement with the tongue to limit upward movement of said end of the arm beyond a position in which the pin will still be disposed in an opening of a clevis plate carried by the tongue, so that the pin will be properly disposed for movement into the draw bar opening. For lifting the draw bar there is provided an elongated handle adjustable as to length, extending upwardly at an angle to the arm, and fixedly connected between the handle and arm is a connecting bar also adjustable as to length for the purpose of varying the angularity of the handle to the arm.

Hitching and unhitching a tongued implement is a time-consuming and somewhat annoying task due to the fact that one seated on the tractor must dismount, perform the hitching or unhitching operation, and then return to the seat. Accordingly, the main object of the invention is to provide an improved device, readily operable from the operator's seat, for hitching and unhitching the tongued implement.

Another object is to provide a device of the nature described which will have a novel means for adjustably limiting the upward movement of the arm on which the draw bar engaging drop pin is mounted, the adjustment being adapted to facilitate the interchange of drop pins so that even if a pin is substituted for another of shorter or longer lengths, adjustments can be readily made to still insure that the lower end of the pin does not move upwardly relative to the tongue any more than a predetermined distance.

Another object is to provide a device as stated wherein a particularly effective means is employed for operating the arm between its upper and lower positions, from the operator's seat of the tractor, said means being readily adjustable to vary the angularity of the handle relative to the arm, according to the desires of the particular user and according to the particular size or make of the tractor.

Yet another object is to provide a device of the nature referred to which will be mountable upon a conventional tongue with a minimum amount of difficulty, will not adversely affect the normal use of the tongued implement or of the tractor, will be simply designed so as to be capable of manufacture at low cost, and will be easily operable by the user.

Other objects will appear from the following description, the claims appended thereto, and from the annexed drawing, in which like reference characters designate like parts throughout the several views, and wherein:

Figure 1 is a side elevational view of the device constituting the present invention, the full lines showing the same in position to hitch the tongue to the draw bar, and the dotted lines showing the same in a releasing position;

Figure 2 is a top plan view of the device, showing fragmentarily the tongue and draw bar;

Figure 3 is a view of the device as seen from the line 3—3 of Figure 1; and

Figure 4 is an enlarged, detail sectional view on line 4—4 of Figure 1.

A conventional tractor generally designated T is illustrated as having a rearwardly extending draw bar 10 also of conventional design, having a cross member 12 formed with a series of openings 13. Designated at 14 is the tongue of a wagon or farm implement, this also being, per se, conventional.

At the forward end of the tongue 14, there are secured, to the top and bottom surfaces thereof, flat, forwardly projecting clevis plates 16 adapted to straddle or embrace the cross member 12 on disposition of the tongue in position to be hitched to the tractor.

A flat, elongated plate 18 is secured by bolts 20 to the tongue, a substantial distance inwardly from the forward end thereof, and integrally formed upon the opposite side edge portions of plate 18 are upwardly projecting ears 22, 22 having transversely aligned openings receiving a pivot pin 24, passing through an opening formed in the rear end portion of an elongated arm 26 extending longitudinally of the tongue 14 above the same. At its rear end, the arm 26 has an angular recess 28, receiving a circular adjusting washer 30 having an eccentrically disposed opening receiving a bolt 31 whereby the washer is connected to the arm for rotatable adjustment to selected positions.

Detachably connected to the arm 26 at the front end thereof is a pin means including a head 32 formed integrally with a depending, tapered drop pin 34 extending through a selected opening 13 of the draw bar.

By reason of the construction so far illustrated and described, it will be seen that when the arm 26 is in its lower, full line position of Figure 1, the pin 34 will extend through the vertically aligned openings of the clevis plate 16, and through an opening 13 of the draw bar. As a result, the tongue is effectively hitched to the tractor. In this position of the arm 26, the washer 30 is elevated out of engagement with the top surface of tongue 14.

However, when the arm 26 is elevated to the dotted line position of Figure 1, the pin 34 moves upwardly out of the opening 13, with the lower extremity of the pin being disposed in the opening provided in the upper one of the plate 16. Thus, the pin does not move upwardly any more than is absolutely necessary to disengage the same from opening 13, and further, is maintained in proper position for downward movement of the arm 26 when the tongue is to be again hitched to the draw bar.

This arrangement facilitates a visual determination as to whether the pin is in proper position relative to the draw bar, for lowering into the opening 13.

A hinge 36 is secured to the arm 26 adjacent the pivotal connection of the arm to the tongue, and secured to one leaf of the hinge 36 is an elongated inner handle section 38, the forward end of which overlies the inner end of an elongated outer handle section 40 having at its front end a ring-like handle element 42 so disposed as to be conveniently grasped by one seated upon the operator's seat of the tractor.

Connecting bolts 43 are extended through registering openings of sections 38, 40, and have been designated at 43. It will be understood, in this regard, that one or

the other of the sections is provided with a longitudinal series of openings, so that the connecting bolts 43 can extend through selected openings of the series, thereby to adjust the overall length of the handle defined by the sections 38, 40.

Bolted to the underside of the forward handle section 40, intermediate opposite ends thereof, is an elongated connecting bar section 44, bolted to a lower connecting bar section 46 which, at its lower end, is fixedly secured to the forward end portion of the arm 26. The sections 44, 46 can be adjusted longitudinally of one another, through the provision of a series of openings in one or both of these sections, so that the connecting bar defined by the sections 44, 46 can be adjusted as to length.

By reason of this arrangement, it will be seen that the handle is fixedly connected to the arm, and extends in acute-angular relationship to said arm. The angularity of the handle to the arm can be varied as desired, by selective shortening or lengthening of the handle and the associated connecting bar. This is desirable so that the handle element 42 will be so disposed as to be readily accessible to the operator seated upon the driver's seat of the tractor. Further, the driver's seat in one tractor may be differently positioned as compared to a driver's seat in another tractor, again making adjustment of the handle position desirable.

In use, when it is desired to unhitch the tongue from the draw bar, the handle element 42 is grasped and swung upwardly. This swings the handle to the dotted line position of Figure 1, thereby elevating arm 26 to disengage the pin 34 from opening 13.

The hitching of the implement to the tractor is accomplished in the same way, that is, after the tractor has been backed up to a proper position, the handle 42 is swung upwardly and the tractor is backed up slowly to dispose the opening 13 below the now elevated pin 34. The handle 42 is now released, and arm 26 will gravitate to engage pin 34 in opening 13.

It will be understood that if desired, the pin 34 can be removed and a different pin, shorter or longer than the first pin, substituted therefor. When this is done, adjustment in the position of the washer 30 is made, so that regardless of the length of the drop pin, it will still not swing upwardly beyond a position in which the lower extremity is disposed just above the plane of the top surface of the draw bar 10.

Any of various means can be employed to connect the device to the tongue, of course, and the plate 18

and ears 22 can, if desired, not be used. Instead, there may be provided a clamp for removably engaging the mount of the arm 26 with the tongue. Various other means can also be employed to advantage.

5. What is claimed is:

1. A hitch for connecting the tongue of an implement to a tractor draw bar having an opening, comprising: an arm adapted to extend longitudinally of and above the tongue; a drop pin on one end of the arm adapted to engage in said opening of the draw bar on downward swinging of the arm; means for mounting the arm upon the tongue for up-and-down swinging movement; handle means projecting upwardly from the arm to extend adjacent the seat of a tractor, for raising and lowering the arm; and means on the opposite end of the arm for engaging the tongue on upward swinging movement of the arm, to limit said upward swinging movement, comprising a washer eccentrically mounted upon said other end of the arm for rotation about an axis extending transversely of the arm, said washer, in selected positions to which it is rotatably adjusted, correspondingly adjusting the extent of upward swinging movement of the arm beyond a position in which the lower end of the drop pin is disposed substantially coplanar with the top surface of the tongue.

2. A hitch for connecting the tongue of an implement to a tractor draw bar having an opening, comprising: an arm adapted to extend longitudinally of and above the tongue; a drop pin on one end of the arm adapted to engage in said opening of the draw bar on downward swinging of the arm; means for mounting the arm upon the tongue for up-and-down swinging movement; and handle means projecting upwardly from the arm to extend adjacent the seat of a tractor, for raising and lowering the arm, said handle means comprising an elongated handle extending angularly to the arm and a connecting bar connected between the handle and arm, said handle being adjustable as to length, and having a hinge connection at one end to the arm, the connecting bar being adjustable as to length, thus to adjust the angularity of the handle relative to the arm responsive to an adjustment in the length of the connecting bar.
